UNITED STATES PATENT OFFICE.

FLORENCE McCARTHY CLERKE, OF MIDDLE PARK, AUSTRALIA.

CLOTHES PEG.

Application filed March 24, 1926, Serial No. 97,125, and in Australia April 9, 1925.

This invention relates to improvements in clothes pegs and consists in the provision of means for making a double ended peg that is intended to be used in place of the ordinary or dolly peg now in general use.

The dolly peg is objectionable on account of its liability to split but I have found it possible to provide by my invention a peg that will not be so liable to break and which, moreover, shall be double ended, with the attendant advantages of such a construction.

Accordingly, therefore, I form two pieces of wood, bone or other suitable material in such a way that when placed together, side by side, the pieces will not touch except at the centre where a slight boss is formed and which acts as a fulcrum to each piece and permits of each rocking slightly upon the other. At this central or medial part of each piece a stout binding is placed to hold the pieces together thus forming a double ended peg having in each end a certain resiliency and considerable strength.

The binding may be of stout wire or a strap of metal suitably prepared and clamped or otherwise secured on the wooden or other pieces forming the peg.

But in order to fully understand the invention reference is made to the accompanying drawings, in which

Fig. 1 is a perspective view of the improved double ended peg.

Fig. 2 is a longitudinal sectional elevation of the same, and

Fig. 3 shows two ways of applying the peg in practise.

Two separate pieces 4 of wood or other material are taken and formed with flaring ends and a medial boss 5 so that either piece need not touch the other except at the boss upon which part each piece will be capable of rocking upon the other. While being retained in this parallel position the two pieces are secured together such as by the wire 6, a strap or other suitable means. When so secured, the parts will still be capa-

ble of a slight rocking movement the one on the other and thus, when one end of the peg is placed on a line or support, the opposite end will close prior to any serious bending strain being placed on the other end. The peg will be formed and hollowed out sufficiently to easily receive the wire or other clothes line and to grip the same when inserted in peg.

In the laundry treatment of delicate fabrics this peg will be found especially useful as such articles may be pegged out in the manner shown in Fig. 3, that is to say, by first placing the fabric in one end of the peg, the other end of which is then secured to the clothes line from below, thus tending to tighten the legs of the peg upon the article without damage hereto. While I prefer to make the pieces 4 separately the double ended peg may, nevertheless, be formed from one piece of wood that will remain solid at the medial part and bound or secured thereat, but this is not to be recommended.

Having now described my invention, what I claim as new and desire to secure by Letters Patent is:—

1. A double ended peg made up of the combination of two pieces of wood having outwardly flaring ends, a medial boss on each piece abutting one on the other to permit of a slight rocking movement between the two parts and means for securing the pieces together.

2. A double ended peg made up of the combination of two pieces of wood having flaring ends, a medial boss on each piece abutting one on the other and capable of a slight rocking movement one on the other when placed parallel boss to boss and a wire strap or band placed about such medial parts to hold the two pieces together.

In testimony whereof I have signed my name to this specification.

FLORENCE McCARTHY CLERKE.
